United States Patent Office

Des. 185,056
Patented May 5, 1959

185,056

WALLET

Victor Arkin, Los Angeles, Calif.

Application February 10, 1956, Serial No. 40,109

Term of patent 3½ years

(Cl. D87—3)

Fig. 1 is a top plan view of the wallet, showing my new design;

Fig. 2 is an edge view looking in the direction of the arrow 2, the opposite parallel edge having the same appearance;

Fig. 3 is an end view looking in the direction of the arrow 3 of Fig. 1;

Fig. 4 is an end view looking in the direction of the arrow 4 of Fig. 1;

Fig. 5 is a perspective view of the wallet in open position; and

Fig. 6 is a perspective view from the opposite end. I claim:

The ornamental design for a wallet, substantially as shown.
